Assistant Examiner — Michelle Marquart Christeon

(74) *Attorney, Agent, or Firm* — West & Associates, A PC; Stuart J. West; Charlotte Rodeen-Dickert

(57) **CLAIM**

The ornamental design for a breast implant enhancement device, as shown and described.

DESCRIPTION

FIG. 1 is a rear, perspective view of a breast implant enhancement device.

FIG. 2 is a front, perspective view thereof.

FIG. 3 is a rear view thereof.

FIG. 4 is a front view thereof.

FIG. 5 is a side view thereof.

FIG. 6 is a side view thereof.

FIG. 7 is a top view thereof.

FIG. 8 is a bottom view thereof; and,

FIG. 9 is a side view, in use.

The broken lines form no part of the claimed design. The dash-dash broken lines in the drawings depict portions of the breast implant enhancement device that form no part of the claimed design. The dot-dash broken lines depict a boundary of claimed design and form no part thereof.

1 Claim, 9 Drawing Sheets
